Aronson & Aronson.

UNITED STATES PATENT OFFICE.

LEWIS E. WEGNER, OF HAGERSTOWN, MARYLAND.

TONGS.

Application filed June 8, 1921. Serial No. 475,885.

To all whom it may concern:

Be it known that I, LEWIS E. WEGNER, a citizen of the United States, residing in Hagerstown, Maryland, have invented certain 5 Improvements in Tongs, of which the following is a specification.

My invention relates to improvements in blacksmith tongs, the object of my invention being to provide tongs having novel and 10 superior gripping means rendering them adaptable to numerous different types of work and insuring a tight grip upon the held article.

The invention will be readily understood 15 by reference to the attached drawings, in which:

Figures 1 and 3, are side views of tongs made in accordance with my invention;

Fig. 2, is a top view of the tongs, and

Fig. 4, is an end view.

My tongs consist of the usual levers or handles 1 and 2, which are pivoted near one end by means of a spindle 3, and whose ends, 4 and 5 respectively, adjacent the pivot 3 are 25 formed to constitute a pair of jaws between which articles may be gripped. In the present instance these ends 4 and 5 are provided with lateral extensions 6 and 7 respectively, said extension 7 having its inner face convex 30 and the extension 6 being wider than the said extension 7 and having its inner face concave to correspond substantially with the inner convex surface of the arm 7. The opposed faces of these extensions 6 and 7 are 35 separated slightly from each other when the jaws are closed except at the tips, and there are in the faces thereof laterally and oppositely disposed grooves 8 which provide sockets for the reception of articles which it 40 is desired to hold between the jaws.

To effect the concavity of the extension 6, the said extension in the present instance is grooved longitudinally, and this groove 9 is extended across the face of the jaw 4. Upon 45 the opposed face of the jaw is a substantially semicircular projection 10 which, when the

jaws are closed, fits into the said groove, as most clearly shown in Fig. 3, said projection preferably being such that when the tip ends 4^a and 5^a of the jaws come together, the apex 50 of the projection 10 lies in contact with or close to the face of the opposite jaw 4. Lateral grooves 11 oppositely disposed in the jaws 4 and 5 provide sockets for the reception of articles held therein, and there are 55 also provided oppositely disposed longitudinal grooves 12 for the same purpose.

It has been found that with this combination of elements a particularly tight grip may be had upon articles of substantially 60 any shape, there being in practically every instance a three-point contact between the jaws and article, and with a minimum of effort applied to the handles 1 and 2, to hold them together, a firm grip may be retained 65 upon the articles held between the jaws.

I claim:

1. Tongs comprising a pair of pivotally connected cooperating jaws, one of said jaws having on its working face a substantially 70 hemispherical projection, substantially as described.

2. Tongs comprising a pair of pivotally connected cooperating jaws each having a lateral elongated projection which together 75 constitute additional jaws, the tips of each pair of jaws being turned in so as to meet coincidently with each other and ahead of the working faces whereby the latter are held slightly separated, and a substantially 80 hemispherical projection on the face of one of the jaws.

3. Tongs comprising a pair of pivotally connected jaws, adjacently disposed extensions on said jaws, the face of one of said extensions being grooved longitudinally and said groove extending across the face of the jaw, and a substantially hemispherical projection on the face of said other jaw adapted to register with said groove.

LEWIS E. WEGNER.
